EXPANSION JOINT FOR ROADWAYS

Russell C. Olmsted, Norwood, N. J.

Application March 17, 1938, Serial No. 196,351

4 Claims.

(Cl. 94—18)

This invention relates to new and useful improvements in roadways and similar passageways and more particularly it pertains to a new and novel construction of expansion joint therefor.

Roadways, driveways and similar passageways, especially when constructed from concrete, are formed in sections commonly called slabs. In the building of such roadways, it is the practice to leave a space between the adjacent edges of the several slabs, which space is filled with a suitable packing material intended to exclude the elements from the joint. This packing material is generally of a compressible nature which will permit of expansion of the slabs and a consequent compressing of the packing material without resulting injury to the slabs.

One object of the present invention is to improve the construction of roadway joints and to render such joints more effective for the purpose intended.

Another object of the invention is to provide a new and novel construction of dowel bar and support therefor, which will permit of relative linear movement of the slabs of a cement roadway and yet, prevent relative vertical movement thereto.

A feature of the present invention resides in a novel construction and arrangement of parts whereby the structure is maintained rigidly in a set-up position which the structure will maintain during the pouring or forming of the slabs of the roadway.

A further feature of the invention resides in a novel construction which will permit of the ready assembly of the structure upon the sub-grade at the location where the roadway is being formed.

Still another feature of the invention resides in a construction and arrangement of parts which permits of a choice of pre-formed packing or sealing elements, or sealing means of the poured type.

Other features of the invention relate to certain novel and improved construction, arrangements and combinations of parts hereinafter described and particularly pointed out in the claims, the advantages of which will be readily understood and appreciated by those skilled in the art.

The invention will be clearly understood from the accompanying drawings illustrating the invention in its preferred forms and the following

detailed description of the constructions therein illustrated.

In the drawings:

Figure 1 is a fragmentary sectional view of a roadway illustrating the device of the present invention in elevation,

Figure 2 is a vertical sectional view taken substantially on the line 2—2 of Figure 1,

Figure 3 is a view similar to Figure 2 taken substantially on the line 3—3 of Figure 1,

Figure 4 is a detail vertical sectional view of one of the dowel bar supporting trackways and guides,

Figure 5 is a vertical detail sectional view taken substantially on the line 5—5 of Figure 1,

Figure 6 is a distended perspective view illustrating a portion of the invention,

Figure 7 is a detail perspective view illustrating a modified form of the invention,

Figure 8 is a fragmentary sectional view of a roadway illustrating the modified form of Figure 7 in position therein,

Figure 9 is a view in elevation illustrating an element employed in the modified form of the invention,

Figure 10 is a fragmentary sectional view showing the modified form of the invention in longitudinal section, and;

Figure 11 is a detail perspective view.

Referring to the drawings, and particularly to Figures 1 through 6 thereof, the reference numeral 15 designates the sub-grade of the roadway, 16 and 17 designating slabs of the roadway proper. Interposed between the adjacent edges of the slabs is a supporting packing material B, to be hereinafter more specifically described.

In carrying out the invention, I employ dowel bars 18 and while I have herein shown these dowel bars as being of I-beam construction, it is to be understood that dowel bars of other cross-sectional shapes, such for example as bulb-beams or the like, may be employed. I prefer, however, to use dowel bars of standard forms in order to maintain an economical construction.

In carrying out the present invention, I place along the roadway, supporting members 19 which in the present instance are shown as of angle-iron construction. These supporting members are placed in pairs with the members in each pair in parallelism and spaced from each other in such a manner as to occupy positions upon opposite sides of a joint between slabs, when the roadway is formed.

In connection with the improved joint, I employ dowel bar supporting trackways 20. Each of these dowel bar supporting trackways is of channel form and consists of a vertical portion 21 and a right angular portion 22 extending normally substantially parallel with the top surface of the sub-grade 15, but spaced therefrom.

These dowel bar supporting trackways are secured to the support 19 by means of bolts 23 which pass through the vertical wall 24 of the supports 19 and through the vertical portion 21 of the dowel bar supporting trackway, as best illustrated in Figures 1 and 6.

In securing the dowel bar supporting trackways to the supports 19, as above described, they are arranged in pairs, and by positioning one trackway of each pair upon each side of the finished joint, and the trackways in each pair in longitudinal alignment with each other, in such a manner that in the assembling of the parts, a dowel bar may be supported by each pair of trackways, and have slidable engagement with one of said trackways.

The dowel bars 18 pass through two opposed channel members 25. As best illustrated in Figure 6, each of these channel members comprises a main body portion 26, side flanges 27 and flanges 28 extending at right angles to the side flanges 27. Furthermore, each of these channels is provided, in its vertical portion 26 with a plurality of suitably spaced openings 30, through which the dowel bars pass, the shape of which openings is determined by the cross-sectional shape of the dowel bars employed.

It is to be understood that the channel members 25 are provided with an opening 30 to receive each of the dowel bars, regardless of the number of dowel bars employed and that in the assembly of the structure, the dowel bars pass through these openings and form a temporary support for the channel members 25.

The reference numeral 31 designates an upper packing strip and 32 designates a lower packing strip. These packing strips 31 and 32 are formed from any suitable material and as best illustrated in Figure 6, they are clamped between the adjacent flanges 28 of the channel members 25, by rods or similar elements 40. The flanges 28 are preferably provided with openings 33, extending therethrough to provide for gripping the packings as they are clamped between their respective flanges 28.

The lower packing strip 32 is, as shown in the drawings, of a width which extends from the lower edge of the channel members to the top surface of the sub-grade 15, the upper packing being of such width that its upper edge will be substantially flush with the top surface of the slabs or finished roadway, this construction and arrangement of parts being clearly illustrated in Figures 2 and 3.

The rods 40, heretofore mentioned as securing the channel members together, extend through the channel members and into the slabs as illustrated at 41 in Figure 5 of the drawings. Intermediate of its ends, each of the rods 40 is weakened as indicated at 42 in the drawings to provide for rupturing of the bars between the channel members upon relative movement of the slabs, thus leaving the channel members free for independent movement while the extension 41 of the rods 40, form means for bonding the channel members to their respective slabs.

The channel members 25 are secured together in opposed relation and this arrangement pro-

vides a chamber 50, between the channel members when they are assembled. This chamber 50 provides a housing for the reception of a compressible packing element 51 which extends throughout the entire length of the channel members and is of such cross-sectional dimensions as to be placed under considerable compression when the channel members are drawn up to position to clamp the packing strips 31 and 32 as heretofore described. The packing element 51 will be provided with suitably shaped openings to permit of the passage therethrough of the dowel bars 18 and the rods 40 in assembling the several parts in their operative position.

While I have herein described the several packing elements 31, 32 and 51 as being of the preformed type, it is to be understood that the invention is not to be limited to use of packings of this type since other packings, such for example as those of the plastic, semi-plastic or poured type may also be employed. For example, when poured packings are employed, the upper packing strip 32 would be replaced by a board, or other element which would be removable after the roadway were formed, leaving a free pouring space between the edges of the slabs which space communicates directly with the chamber 50, it also being understood that in such instances, the packing element 51 would be dispensed with.

The channel members 25 with their packing strips 31, 32 and 51 are clamped in position, as above described, constitute a complete assembly, and the several parts are retained in this assembled position by the bars 40 during the construction of the roadway.

As illustrated in Figure 5, the rods 40 are in the form of threaded bolts and the channel members 25 are shown as clamped between nuts or the like 43 and 44 with the weakened portions 42 of the rods positioned in the chamber 50 between the opposed channel members.

As best illustrated in Figure 6, the trackways are provided with crimped-over portions 35 which pass around the edges of the lower flanges of the dowel bars 18 while the other trackway of each pair is not so formed, the dowel bars merely resting upon said last mentioned trackway of each pair. The reference numeral 36 designates a cap plate which is placed upon the upper flange of the dowel bar and has its side edges crimped as at 37 to embrace the side edges of the upper flange of the dowel bar. The reference numeral 38 designates a shield, which may be formed of any suitable material of which paper or light metal may be cited as good examples. As illustrated in Figure 4, this shield conforms to the shape of the sides of the dowel bar 18 and is secured in position by the crimped portions 35 and 31 respectively, of the supporting trackway and cap plate 36. However, it is to be understood that the crimpings 35 will not in any way interfere with the free sliding movement of the dowel bar relatively to the trackway.

The cap plate 36 has a right angular end 38' which extends downwardly around the outer end of the dowel bar 18 and a filler block 39 is positioned in the outer end of the cap plate 36 upon each side of the dowel bar.

By reference to Figure 3, it will be apparent that this construction provides a housing D, in which one end of the dowel bar is free to slide, even after the concrete forming the slabs has been placed in position to completely enclose the housing, and that the opposite end of the dowel

bar, which is designated **E** in said Figure 3, is not so protected and will, therefore, be securely bonded to, or anchored in the concrete, forming the slab in which this end of the dowel bar is positioned.

In forming my joint for roadways, the dowel bars will be positioned, as above described. However, the housings **D**, in one of which one end of each of the dowel bars will be positioned, will be arranged upon opposite sides of the joint in alternate pairs of supporting trackways. In other words, in one pair of supporting trackways, the housing **D** will be upon one side of the joint, while in each of the next adjacent pairs of trackways, the housings **D** will be upon the opposite side of the joint.

By this construction, each of the dowel bars will be anchored to a slab on one side of the joint, while its other end will be freely movable or slideable in the slab upon the opposite side of the joint.

In practice, the structure is set up in either of the heretofore described manners, the angle-irons **19** and packing strip **32** forming the means by which the structure is supported upon the sub-grade. With the parts of the structure in their set-up position, the concrete forming the slabs **16** and **17** is poured, completely enclosing the structure in the roadway, as illustrated in Figures 2 and 3 of the drawings. As the material of the slabs sets, the entire structure will be bonded to the slabs except of course one end of each dowel bar which of course will be free to slide in the housing in which it is enclosed.

With the parts in the position just described, immediately upon relative movement of the slabs either from expansion or contraction, the rods **40** will part at their weakened portions **42**, whereupon, the slabs will be free to move relatively to one another under temperature variations during which movements, the dowel bars will move with the respective slabs to which they are bonded with their other ends freely movable relatively to the slab in which they are positioned.

In addition to forming means for supporting and guiding the sliding movements of the dowel bars during movements of the slabs, these trackways and the housings which enclose the freely movable ends of the dowel bars, provide wear surfaces for the movable ends of the dowel bars, thus preventing wearing away of slabs as a result of the sliding movement between the free ends of the dowel bars and the slabs in which they are positioned.

In Figure 7, I have illustrated a modified form of the invention in which the channel members **25** and **26** are not employed.

In said Figure 7, the dowel bar is designated **60** and is illustrated as of I-beam form. One end of the dowel bar **60** is enclosed in a housing which the other end is exposed to be enclosed in the concrete which forms the adjacent slab in order that the dowel bar may be anchored to this slab. By this construction, one end of each dowel bar is anchored in or bonded to one slab at one end, while its other end is freely slideable relatively to the slab in which it extends by reason of the fact that it is surrounded by the housing which is anchored in the slab and in which the end of the dowel bar is freely slideable.

The housing which encloses the one end of the dowel bars in this form of the invention, consists of a cap-plate **61** having side flanges **62** which embrace the side edges of the top flange of the dowel bar. The reference numeral **63** designates **75** 70

a shield which may be formed from paper, light metal or the like and it is to be understood that there will be one of said shields upon each side of the dowel bar **60**. These shields conform in shape to the sides of the dowel bar and as in the heretofore described form of the invention, extend along the inner faces of the flanges of the dowel bar. The lower flange of the dowel bar rests upon a channel member **64**, the side flanges **65** of which extend upwardly around the edges of the lower flanges of the dowel bar. This channel forms a trackway upon which the free end of the dowel bar may slide and also provides a wear surface upon which the dowel bar slides, thus preventing wear or damage to the slab.

15 Filler blocks **66** are employed at the end of the dowel bar, there being one of said filler blocks upon each side of the dowel bar as in the heretofore described form of the invention.

The cap plate **61**, the channel track member **64**, the shields and the filler block are all held in their assembled position, by straps or the like **67**. Two of these straps **67** are passed around the assembly and after they have been placed in position, they are distorted inwardly of the dowel bar as designated at **68**, in order to tighten them about the housing and hold the same in shape.

20 This assembly, as shown in Figure 7, may be supported in any desired manner so that the dowel bar **60** will bridge the joint between two slabs in the finished roadway with one of its ends securely bonded to one of the slabs and its other end freely slideable in the housing which is embedded in the next adjacent slab.

25 It is, of course, to be understood that the housings which enclose the ends of the dowel bars will be staggered or positioned in such a manner that alternate dowel bars will have their housings and bonded ends in the same slabs.

30 In Figures 8 and 9, I have illustrated a slightly modified form of the invention, which differs only from the form shown in Figures 1 through 6, in that in lieu of the channel members **25** and **26**, I employ plates **70** which may be either strips of sufficient length to extend throughout the length of the joint, or may be washer-like members **71** of the type illustrated in Figure 9 of the drawings.

35 In this form of the invention, I employ a lower packing strip **72** and an upper packing strip **73**, or a packing strip of a single width extending from the sub-grade **15**, to the surface of the finished roadway, may be employed. In either construction, the packing strip is formed with openings through which the dowel bars pass and the plates **70** or the washer-like members **71** effectively preventing bonding together of the slabs when the concrete is poured to form the slabs. This is true, since the plates **70** or washer-like members **71** have openings **72** therein which are of a shape and size, snugly to fit the dowel bar yet without offering any resistance to its movement therethrough.

40 In Figures 10 and 11, I have illustrated still another modified form of the invention in which washer-like plates are employed, which washer-like plates are in the form of integral extensions of the trackways upon which the dowel bars are supported.

45 The trackways are designated **80**, in these figures and in the form of the invention illustrated in Figures 1 to 6 of the drawings, they comprise a channel shaped member bent as at **81** to provide a vertical portion **82** and a horizontal portion **83**. These trackways are supported upon the sub-grade **15** by angle bars **19** in the manner hereto-

fore described and as illustrated in Figure 10 of the drawings.

Upon the free end of each trackway, there is a plate 84 in the form of an integral extension of the trackway and said plates are provided with openings 85 therethrough which correspond in shape to the cross-sectional shape of the dowel bar in connection with which they are employed. The plates 84 serve to engage opposite sides of the packing strip 86 to retain it in position and also to prevent the flow of concrete through the dowel bar openings in the packing strip and thus prevent inter-bonding of the slabs at the joints.

The dowel bars, in this form of the invention, are supported upon the trackways 80 and one end of each is mounted within a housing in the manner heretofore described to permit of said end having free sliding movement in the slab in which it is mounted.

From the foregoing, it is apparent that the present invention provides a new and novel roadway joint structure which is, by its own structure, maintained in a practically rigid unit until such time as the roadway has been completed or at least poured, after which, as a result of expansion or contraction of the slabs, the structure becomes two separate elements each carried by its respective slab and at the same time effectively dividing the roadway into a plurality of slabs, each capable of movement independently of the others.

Furthermore, the invention provides a structure in which wear plates are provided for the movable ends of the dowel bars, thus preventing wearing away of the concrete of the slabs by reason of direct contact of the dowel bars with the walls of the recesses in the slabs in which they are mounted.

The invention also provides a novel construction and arrangement of parts which permits of the use of dowel bars of various standard cross-sectional forms other than circular, the type generally employed in structures of this type.

While the invention has been herein illustrated in its preferred forms, it is to be understood that it is not limited to the specific constructions herein set forth and that it might be carried out in such other forms as rightfully fall within the scope of the appended claims.

Having thus described the invention, what is claimed as new is:

1. An expansion joint structure comprising in combination, a pair of angle irons extending along the roadway sub-grade in spaced parallel relation to each other, dowel bar supporting trackways carried by each of said angle irons with each trackway of one angle iron in longitudinal alignment with a trackway of the other angle iron, a dowel bar supported upon each two aligned trackways, means cooperating with one of the trackways supporting each dowel bar for enclosing one end of the dowel bar carried thereby and opposed channel members supported upon said dowel bars intermediate of the inner ends of the trackways, said opposed channel members having aligned openings for a shape corresponding to the cross-sectional form of the dowel bars to receive the dowel bars and cooperate therewith to form a seal for the space between the opposed channel members.

2. A housing for enclosing the end of a dowel bar in the building of roadways, said housing comprising in combination, a trackway for supporting a dowel bar, a cap-plate for a dowel bar supported upon the trackway, shields extending between the trackway and the cap-plate, and means for retaining said trackway and said cap-plate in operative position upon a dowel bar supported upon the trackway.

3. A housing for enclosing the end of a dowel bar in the building of roadways, said housing comprising in combination, a trackway for supporting a dowel bar, a cap-plate for a dowel bar supported upon the trackway, shields extending between the trackway and the cap-plate, and means for retaining said trackway and said cap-plate in operative position upon a dowel bar supported upon the trackway, said means embracing the entire assembly adjacent the opposite ends thereof.

4. A housing for enclosing the end of a dowel bar in the building of roadways, said housing comprising in combination, a trackway for supporting a dowel bar, a cap-plate for a dowel bar supported upon the trackway, shields extending between the trackway and the cap-plate, and means for retaining said trackway and said cap-plate in operative position upon a dowel bar supported upon the trackway, said means comprising straps embracing the entire assembly and distorted into engagement with the shields.

RUSSELL C. OLMSTED.
